CLAIM

We claim the ornamental design for an information handling system bezel, as shown and described.

DESCRIPTION

FIG. 1 is a front perspective view of the information handling system bezel comprising the present invention; FIG. 2 is a front elevation view thereof;

FIG. 3 is a rear elevation view thereof;

FIG. 4 is a right side view thereof;

FIG. 5 is a left side view thereof;

FIG. 6 is a top view thereof;

FIG. 7 is a bottom view thereof;

FIG. 8 is a bottom perspective view thereof;

FIG. 9 is a front perspective thereof illustrating the appearance of the internal structure when hidden from view by the viewing angle;

FIG. 10 is another front perspective view thereof illustrating the appearance of the internal structure as partially visible by the viewing angle;

FIG. 11 is another front perspective view thereof illustrating the appearance of the internal structure as visible by the viewing angle;

FIG. 12 is an exploded view thereof showing the inner and outer structures separated for ease of illustration; and,

FIG. 13 is another front perspective view thereof shown coupled to the environment of an information handling system. The different angles shown in FIGS. 1-2 and 8-13 illustrate the appearance of a hidden vent that transitions to the appearance of a visible vent.

(Continued)

Broken lines shown in the drawings illustrate portions of the information handling system bezel, and form no part of the claimed design.
